INTERNAL COMBUSTION ENGINE WITH
MEANS FOR REGULATING THE COMPRE-
SSION RATIO

Application April 13, 1937, Serial No. 136,674
In Japan April 13, 1936

3 Claims. (Cl. 123—48)

This invention relates to an internal combustion engine provided with means for varying the compression ratio, so that it is operated always at highest thermal efficiency under various 5 conditions.

In internal combustion engines of the Otto cycle type, the compression ratio is limited within a safety range so as to prevent advanced ignition or detonation even when operating under over- 10 load or when operating with the richest mixture 15 and at a considerably heated condition. Therefore, it is not possible under full load to obtain allowable maximum compression ratio. Under a lighter load, it is desirable that a higher compression ratio be given in view of the decrease of the amount of suction or dilution of the mixture. However, in an old engine with a fixed volume of combustion chamber, it has been unavoidable that, under lighter load, the compression ratio 20 greatly decreases below the maximum compression ratio allowed by the mixture then sucked in, whereby the thermal efficiency of the engine is considerably lowered. Especially for motor vehicles, an engine having large output is used, in view of the fact that quick acceleration is desirable 25 and that the vehicle must run with a comparatively high speed even on bad road or steep ascent road. On the other hand, the majority of the running period of the motor vehicle is on 30 flat road, in which period the engine is operated under a lighter load, about one-fourth of the full load, so that it is unavoidable that there is loss of fuel consumption during such normal period of running.

This invention aims to remove the above-mentioned disadvantage, and it comprises a provision of a movable member in the cylinder head opposite the working piston of the engine, forming a closed liquid chamber behind said movable member, and means for controlling the flow of liquid supplied into said closed chamber according to the working condition of the engine, so that the position of said movable member is altered to vary the effective volume of the combustion chamber. By such means, it is possible to vary the compression ratio according to variation of the load, the engine speed, the mean working pressure, and the nature of fuel, etc., so as to always obtain highest thermal efficiency under varying conditions. Thus, the thermal efficiency is increased under varying conditions, and particularly under a light load. The invention is most advantageously applicable for the engine for motor vehicles. By experiments it has 55 been found that approximately 30% of the fuel

consumption is saved in the motor vehicle equipped with this invention.

Means for varying the compression ratio according to this invention may be arranged in the cylinder head, quite independently of the moving main part of the engine, so that the operation of the main part is by no means affected. Control of the liquid for actuating the movable member is effected merely by opening or closing the passage of the circulating liquid, so that only a slight 10 power is required for the purpose, and the control may be most effectively and readily effected. Moreover, by the circulation of said liquid in the closed chamber, cooling of the movable member may be also effected, whereby attaining a reliable 15 action of the movable member for varying the compression ratio. Any existing engine may be readily re-constructed so as to be equipped with means of this invention by a simple work at a low cost.

The invention will now be fully described with reference to the embodiment shown in the accompanying drawing, which shows in section a V-type multi-cylinder engine constructed according to this invention.

The essential part of this invention comprises a movable member having behind it a liquid chamber, circulating means for supplying liquid into and discharging from said chamber, and a valve mechanism for opening or closing the passages of the said circulating liquid.

Referring to the drawing, 1 designates a cylinder, 2 a cylinder head mounted thereon, and 3 is a piston. The cylinder head 2 is provided with a cavity 4 opposite to the piston 3 and also facing to the inlet valve 5 and exhaust valve (not shown). In said cavity 4 is slidably mounted a piston-like movable member 6. The movable member 6 is integrally formed with a central barrel 7, of which the upper end is inserted into a bore 8 formed in the upper end of the cavity 4. The lower end of the barrel 7 is in communication with the cavity 9 on the rear side of the movable member 6. The cavity 4, together with the movable member 6, forms a closed liquid chamber. The upper wall of the liquid chamber is provided with a liquid outlet port 10.

Upon the upper wall of the liquid chamber is mounted a valve casing 11, in which are provided a liquid inlet valve 12 communicating with the central barrel 7 and a check-valve 13 communicating with the liquid outlet port 10. The liquid inlet valve 12 is seated on a valve seat 14 which is provided with a clearance in a portion thereof, and is in communication with an inlet

port 15' which is connected by means of a pipe 15 to a liquid reservoir 16. In the embodiment shown, the cooling jacket 16 of the engine is utilized as the liquid reservoir. In said pipe 15 is inserted a gear pump 17 which is actuated from the crank-shaft 18 of the engine through any suitable transmission mechanism. The check-valve 13 is connected by means of a pipe 19 to similar check-valve 13 provided on another cylinder. A liquid controlling valve 21 is provided in the port connecting said pipe 19 by means of conduit 20 with the water cooling jacket 16. In the gear pump 17 is provided by-pass 24 which connects the outlet 22 and the inlet 23. In said by-pass 24 is provided a pressure regulating valve 25 normally pressed toward the outlet 22.

Control of the liquid controlling valve 21 may be effected manually as well as automatically. In the embodiment shown, it is automatically controlled through means responsive to variation of the vacuum in the intake pipe of the engine. Secured to the valve casing 11, there is an air-pressure case or short cylinder 26 having a central hollow post 27. Inserted through the bore of said post 27 is a valve presser rod 28 adapted to press the liquid controlling valve 21. To the outer end of the rod 28 is secured a disc 29 pressed outwardly by a spring 30 against the outer closed end of a barrel 31. Said barrel 31 has a working disc 30 or piston 32 which is slidably mounted within the air-pressure cylinder 26 in an air-tight manner. The air-pressure cylinder 26 is connected through a pipe 33 to the suction pipe 34 of the engine.

As the engine operates, the gear pump 17 is also actuated, and the liquid in the water cooling jacket 16 is normally forced into the space at the rear of the movable member 6 through the clearance left in the liquid inlet valve 12. The amount of the circulating liquid thus forced into the liquid chamber behind the movable member varies according to the output of the engine. As it circulates, the temperature of the liquid is lowered, and it acts to cool the movable member 6 and the adjacent portions.

In the no-load condition, as the degree of vacuum in the intake pipe 34 increases, the liquid controlling valve 21 behind the movable member 6 will be closed against the action of the maximum explosion pressure which acts upon the movable member 6, so that the ingress only of the liquid is permitted in the liquid chamber 9, discharge thereof being prevented by said closed valve 21. Therefore, the movable member 6 is gradually lowered, and it stops when the highest compression ratio is obtained, and the circulation of the liquid is stopped. When the engine output increases, the degree of vacuum in the intake pipe decreases according to increase of the explosion pressure, and the liquid discharge valve 21 will be partly opened, permitting fluid to flow through conduit 20 and into jacket 16, whereby the movable member 6 will be slightly moved upwardly during every explosion. On the other hand, the movable member 6 receives a returning movement from the liquid pressure supplied from the gear pump 17. Thus, the movable member 6 partakes up and down vibrating movement, while the liquid behind same is circulated. When the engine output is further increased, the liquid controlling valve 21 is opened wider, so that the distance of the upward movement of the movable member 6 imparted by the explosion pressure exceeds the distance of the downward return movement of the movable member 6 imparted by the pressure liquid, whereby the movable member during every

cycle moves upwardly by a distance equal to the difference of said upward and downward movements. Thus, the compression ratio will gradually decrease, and the maximum explosion pressure will gradually decrease until the distance of the upward movement imparted to the movable member 6 by the explosion pressure becomes equal to the distance of the return movement imparted by the pressure liquid. Then, the movable member 6 will be merely vibrated at the position maintaining an intermediate compression ratio, the pressure liquid being circulated. When the load increases and the engine is operated for the full output, the degree of the vacuum in the intake pipe will become extremely weak, and the movable member 6 is rapidly moved upwardly, permitting the free discharge of the pressure liquid behind the same, whereby it is maintained at the position of the lowest compression ratio, the pressure liquid being subjected to full circulation. In this condition, the discharge of the pressure liquid being fully permitted, the movable member 6 ceases to vibrate, and the pressure liquid freely flows into and out of the liquid chamber 9, solely serving as the cooling means.

In the multi-cylinder engine as shown in the drawing, only a single set of liquid circulating means and liquid controlling valve device is sufficient for the purpose, regardless of the number of cylinders, the liquid inlet port 15' and the check-valve passage 19 for each cylinder being connected to each other. By such measure, it is possible to equalize the amount of pressure liquid supplied to all liquid chambers 9 behind the movable members 6 throughout the entire engine.

In order to attain smooth movement of the movable member 6 and to prevent leakage of the explosion gas, the sliding surface of the movable member 6 is preferably provided with suitable packings 35 and piston ring 36 as shown in the drawing.

What we claim is:—

1. An internal combustion engine with means for regulating the compression ratio, comprising a movable member facing to the combustion chamber, a closed chamber provided directly behind said movable member and filled with a pressure liquid, said closed liquid chamber being provided with liquid inlet and outlet ports connected with a liquid reservoir forming a liquid circuit, means inserted in said liquid circuit for circulating the pressure liquid, a controlling valve in said liquid circuit, and means responsive to engine operation conditions for controlling said controlling valve for varying the amount of the pressure liquid in said closed liquid chamber behind the movable member, whereby varying the position of the latter.

2. An internal combustion engine with means for regulating the compression ratio, comprising a movable member facing to the combustion chamber, a closed chamber provided directly behind said movable member and filled with pressure water, said closed liquid chamber being provided with liquid inlet and outlet ports connected with an engine cylinder water jacket forming a liquid circuit, means inserted in said liquid circuit for circulating the pressure water, a controlling valve in said liquid circuit, and means responsive to the vacuum in the intake pipe of the engine for controlling said controlling valve for varying the amount of the pressure liquid in said closed liquid chamber behind the movable member, whereby varying the position of the latter.

3. A multi-cylinder internal combustion engine,

comprising movable members facing to the combustion chambers, a closed chamber provided directly behind each of said movable members, each closed chamber having liquid inlet and outlet ports for supplying pressure liquid into or discharging from said chamber, means for connecting said inlet and outlet ports for each cylinder to similar liquid inlet and outlet ports for another cylinder, a common means inserted in said con-

necting means for circulating the pressure liquid, a common controlling valve inserted in the liquid circuit including said closed chamber and inlet and outlet ports, and a common means for controlling said controlling valve, whereby the compression ratio is simultaneously regulated throughout all the cylinders. 5
